UNITED STATES PATENT OFFICE.

JOHN SHECKLER, OF WASHINGTON, KANSAS.

HAND-CULTIVATOR.

1,135,062.

Specification of Letters Patent. Patented Apr. 13, 1915.

Application filed December 15, 1914. Serial No. 877,400.

To all whom it may concern:

Be it known that I, JOHN SHECKLER, a citizen of the United States, residing at Washington, in the county of Washington, 5 and State of Kansas, have invented a new and useful Hand-Cultivator, of which the following is a specification.

The invention relates to improvements in hand cultivators.

10 The object of the present invention is to improve the construction of hand cultivators and to provide a pushing device of light, strong, durable, and comparatively inexpensive construction, adapted to be readily applied to single wheel garden plows, and similar hand cultivators, seeders, and the like, and capable of enabling the operator to throw the weight of his body against the machine, whereby the same may be operated 15 with greater ease and less labor.

20 A further object of the invention is to provide a pushing device of this character adapted to be readily adjusted independently of the handles of a cultivator to arrange it against different portions of the body, and equipped with a cushion, housed within the pushing device, and adapted to relieve the operator of jars and jolts when the cultivator comes in contact with a rock 25 or other obstruction.

With these and other objects in view the invention consists in the construction and novel combination of parts hereinafter fully described, illustrated in the accompanying 30 drawing, and pointed out in the claim here-
to appended, it being understood that various changes in the form, proportion, size and minor details of construction, within the scope of the claim, may be resorted to 35 without departing from the spirit or sacrificing any of the advantages of the invention.

In the drawing:—Figure 1 is a perspective view of a handle cultivator provided 40 with a pushing device constructed in accordance with this invention. Fig. 2 is a longitudinal sectional view of the pushing device detached. Fig. 3 is a transverse sectional view on the line 3—3 of Fig. 2.

45 Like numerals of reference designate corresponding parts in all the figures of the drawing.

In the accompanying drawing, in which is illustrated the preferred embodiment of 50 the invention, the pushing device, which is

located above and is adjustable independently of the handles 1 of a hand cultivator, comprises in its construction a tubular rod or stem 2 arranged at an inclination and having its lower or front end flattened and secured between a pair of spaced plates 3 forming a front fork for straddling the wheel 4 of the hand cultivator and having downwardly curved front terminals 5 which are mounted upon the axle 6 of the front 60 wheel 4. The downward curve of the forks of the push bar is designed to throw the push bar above a seeder or any other machine on which the push bar may be used. The plates 3, which are angularly bent at 65 their inner portions 7 to space them the proper distance apart, are provided at their lower terminals with bearing openings 8 for the reception of the axle 6, and the said plates 3 have their lower terminals fitted 70 against the outer faces of the side bars or members 9 of the plow beam 10 of the hand cultivator. This construction enables the pushing device to be readily applied to various implements such as garden plows, cultivators, seeders, and the like having a single 75 supporting wheel.

The upper rear portion of the tubular stem or rod 2 receives a slidable tube 11 which carries a curved body plate 12, riveted 80 or otherwise secured to laterally extending ears or lugs 13 projecting from the rear end of the tube 11. The slidable sleeve and the tubular rod or stem receive and form a housing for a coiled cushioning spring 14, interposed between the curved body plate 12 and a stop pin or rivet 15, disposed transversely of the rod or stem 2 and piercing the opposite sides thereof. The cushioning spring, which is housed and protected by the telescopic tubular members of the pushing device, is adapted to relieve the operator of 85 jolts and jars when the cultivator strikes a stone or other obstruction. The tubular members of the pushing device are limited 90 in their sliding or telescopic action by means of a pin or bolt 16, carried by and piercing the tube 11 and operating in longitudinal slots 17 in the upper and lower walls of the tubular rod or stem 2. The slots 17 are of 95 sufficient length to permit the necessary relative sliding movement of the tubular members of the pushing device to secure the desired cushioning action of the spring 14, and the fastening device 16, which operates in 100 105 110

the slot 17, is preferably in the form of a bolt to enable the tubular members to be readily separated to afford access to the cushioning spring. The curved body plate, 5 which presents a rear concave face to conform to the configuration of the upper portion of the body of a person, is provided with a soft pad 18 preferably formed by upholstering the curved plate, but any other suitable pad may be employed for protecting the body of the operator.

In the operation of the cultivator the operator grasps the handles 1 in the usual manner and places the pad of the pushing device against his chest, the pushing device being adapted to swing upwardly and downwardly on the axles of the cultivator, independently of the handles 1, to arrange the pad at the desired portion of the body. 15 This will enable the operator to throw his weight against the cultivator for forcing the same through the soil and the pushing device will enable the operator to force the cultivator through the ground with greater ease and less labor than is possible by using only the plow handles. Also, the housing of the spring protects the latter and prevents the same from being affected by the weather or accidentally broken. 20 25

What is claimed is:—

In combination with an implement of the class described including a supporting wheel and an axle, of a tubular stem disposed longitudinally of the implement and provided at its front end with forwardly extending side plates, said plates being spaced apart to form a fork to straddle the wheel and having downwardly extending curved terminals mounted on the said axle, said tubular stem being also provided at its upper 30 35 40 portion with a longitudinal slot, a rear tube slidable on the rear portion of the said stem and having a fastening device operating in the said slot to limit the relative sliding movement of the same and the tube, a padded body plate mounted on and carried by the rear end of the tube, and a coiled spring housed within the stem and the tube and arranged to cushion the latter and the body plate, the pad on the latter covering the entire rear face thereof. 45 50

In testimony, that I claim the foregoing as my own, I have hereto affixed my signature in the presence of two witnesses.

JOHN SHECKLER.
